UNITED STATES PATENT OFFICE

LASLO BAROTA, OF PERRYOPOLIS, PENNSYLVANIA

GUARD BOOTH

Application filed March 23, 1931. Serial No. 524,603.

My invention relates to a guard booth designed for housing a watchman or guard employed for protecting property, particularly financial institutions, and the like, against robbery.

Important objects of the invention are to provide a guard booth of the character described, which is puncture proof against bullets to protect the guard housed therein, which may be readily shifted by the guard himself to establish a view therefrom that is most advantageous for the purposes intended, and which may be conveniently assembled or taken apart when required facilitating its transportation or storage.

Further objects of the invention are to provide a device of the class stated, which is simple in its construction and arrangement, durable and efficient in its use, compact, attractive in appearance, which embodies novel means for sounding an alarm, and which is comparatively inexpensive to manufacture and install.

With the foregoing and other objects in view which will appear as the description proceeds, the invention consists of the novel combination and arrangement of parts, and in the details of construction hereinafter described and claimed, but it is to be understood that changes in the precise embodiment of the invention may be resorted to that come within the scope of the claim hereunto appended.

In the drawings wherein like numerals of reference designate corresponding parts throughout the several views:—

Figure 1 is a front elevational view of a guard booth, constructed in accordance with the invention.

Figure 2 is a vertical sectional view on line 2—2, Figure 1.

Figure 3 is a top plan view of the base plate.

Figure 4 is a transverse sectional view on line 4—4, Figure 2.

Referring in detail to the drawings 1 denotes the entire booth, which is preferably, though not essentially, rectangular in contour. The booth 1 is constructed from sheet metal of such strength and thickness to ren-

der same puncture proof against bullets fired from any type of gun.

The booth 1 consists of a front wall 2, a rear wall 3, a pair of side walls 4, a top 5, and a floor 6. The edge margins of the top 5 and of the floor 6 are bent to extend at right angles to the latter to provide the flanges, respectively indicated at 7 and 8, which overlap and engage the outer side of respective end edge margins of all of the walls 2, 3, and 4. The walls are secured to the flanges 7 and 8 by means of the screws 9, providing a rigid booth structure but permitting the latter to be readily assembled or taken apart when required.

The rear wall 3 is provided with a door 10 having suitable latching and locking elements 10'. The door 10 is preferably hinged, and permits access to and from the booth 1. The top 5 is provided with a plurality of openings 11 providing ventilation for the occupant of the booth 1.

A window 12, constructed from bullet and shatter proof glass, is mounted in each of the walls 2, 4, and in the door 10. The windows 12 are all disposed at a height to accommodate same to the view of the occupant while in the standing position, and provide the latter with a view from all sides of the structure.

The booth 1 is supported on swivelled casters 13, which are secured to the bottom 6 adjacent to respective corners of the latter. The casters 13 are preferably provided with rubber tires to effect the silent operation thereof.

The booth 1 is mounted on a sheet metal base plate 14, which is provided with apertures 15 for the reception of bolts for securing the base plate 14 in fixed position to the floor of the structure in which the booth is to be located.

A large wheel gear 16 is mounted flatly on the center of the base plate 14 and secured to the latter by bolts 17, or in any other suitable manner. The wheel gear 16 is provided with an upwardly extending shank 18, which is disposed at the axial center thereof. The shank 18 extends into a bearing plate 19, which is welded or otherwise fixed in posi-

tion to the underside of the floor 6. The engagement of the shank 18 in the bearing plate 19 maintains the booth 1 in position on the base plate 14 but permits the rotation of said booth 1 on the latter.

A pinion gear 20, fixed to the lower end of a vertically extending shaft 21, meshes with the wheel gear 16. The shaft 21 is disposed in the front of the booth 1, and extends 10 through the floor 6. The shaft 21 is revolvably mounted in a bearing 22 fixed to the front wall 2, and in a bearing 23 welded to the under side of the floor 6.

An operating wheel 24 is fixed to the upper end of the shaft 21 positioning the former directly below and adjacent to the window 12 in the front wall 2. The rotation of the operating wheel 24 will cause likewise rotation to the pinion gear 20. The pinion gear 20 being in mesh with the fixed wheel gear 16, will travel around the latter thereby imparting rotation to the entire booth 1 in either direction. As the booth 1 is supported on the swivelled casters 13 the latter will travel in 25 the base plate 14 along the dash line, as indicated at 25 in Figure 3, and will shift with comparative ease.

A small aperture 26 is provided in the front wall 2 preferably adjacent to the window 12 in the latter. The aperture 26 provides an opening through which the guard is enabled to shoot when required. As the operating wheel 24, the front wall window 12, and the aperture 26 are all positioned in close proximity to each other, the guard is enabled to shift the booth 1 while engaged in shooting from the aperture 26, with a full view through the said window 12.

The gear wheel 16 is formed with an aperture 27 which extends through the shank 18 and communicates with an opening 28 in the floor 6, of the booth 1 and with an opening in the base plate 14. The aperture 27 is provided for the passage of electrical conductors 29 connecting with some suitable audible alarm system for acquainting the occupants of the building that something is amiss. An operating switch 30, joining with the conductors 29 is mounted in the floor opening 28, 50 and may be depressed by the foot of the guard to operate the alarm system.

While the booth 1 is herein illustrated and described as being supported on the casters 13 and mounted on a fixed base plate 14, it 55 will be apparent that the said booth may be suspended from the top thereof, or in any other manner to best meet conditions found in practice.

The present invention provides a most efficient device of its kind, which will, with an alert guard, secure any institution equipped therewith against banditry.

What I claim is:

In combination, a guard booth comprising 65 a front wall, a rear wall, a pair of side walls,

a top including a flange overlapping and being secured to the upper ends of all of said walls, a floor including a flange overlapping and being secured to the lower ends of all of said walls, a door carried by one of said walls, 70 a window mounted in said front and side walls and in said door, a fixed base plate, casters supporting the booth on said base plate, said front wall being provided with a comparatively small opening disposed adjacent to the window in said front wall, means operable from within the booth for rotating the latter in either direction on said base plate, a wheel gear fixed on said base plate, a pinion gear meshing with said wheel gear, and an operating element connecting with said pinion gear for rotating the latter to impart rotation of the booth on said base plate.

In testimony whereof I affix my signature.

LASLO BAROTA.
